UNITED STATES PATENT OFFICE.

SIDNEY D. WALDON, OF DETROIT, MICHIGAN, ASSIGNOR TO PACKARD MOTOR CAR COMPANY, OF DETROIT, MICHIGAN, A CORPORATION OF MICHIGAN

HYDROCARBON-MOTOR.

1,143,001.

Specification of Letters Patent. Patented June 15, 1915.

Application filed July 5, 1913. Serial No. 777,479.

To all whom it may concern:

Be it known that I, SIDNEY D. WALDON, a citizen of the United States, and resident of Detroit, Wayne county, State of Michigan, have invented certain new and useful Improvements in Hydrocarbon-Motors, of which the following is a specification.

This invention relates to hydrocarbon motors, and particularly to the means for controlling the oiling system thereof.

Heretofore oiling systems have been employed on hydrocarbon motors in which there are a main oil feed to the principal bearings of the motor and an auxiliary oil feed which gives an extra supply of oil to the motor or in some cases feeds the oil direct to the cylinder walls. The auxiliary oil feed is usually adapted to become operative when the motor is running at high speed or is pulling hard. None of the oiling systems heretofore employed, however, have any provision for increasing the oil supply or operating the auxiliary feed when the motor is cold, as when starting, or for cutting down the oil feed or closing the auxiliary feed when the motor is hot or is running under normal conditions. After a motor has been standing for some time and has become cold, most of the oil has of course drained from the bearings into the crank case and it is very desirable, therefore, that an unusual supply of oil should be fed to the various bearings of the motor as it is started under these conditions. This unusual supply should of course be cut down as soon as the motor has started or has warmed up so that it is running normally.

It is one of the objects of the present invention to provide means for feeding an unusual supply of oil to the motor under the above referred to conditions of starting, and to make such means substantially automatic in its action.

Another object of the invention is to provide an auxiliary oiling system for a hydrocarbon motor, which system shall be controlled both by the means which control the richness of the mixture passing to the motor and the means for controlling the throttle valve of the motor.

Other objects of the invention will be ap-

parent from the following description taken in connection with the drawings which form a part of this specification, and in which:—

Figure 1 is a side elevation of a motor embodying this invention, having parts cut away to illustrate certain interior construction; Fig. 2 is a slightly enlarged view of most of the operating parts shown in Fig. 1 and illustrating these parts in a different position; and Fig. 3 is a sectional view through the oil valve.

Referring to the drawings, 10 represents a motor base or crank case upon which are mounted the cylinders 11, in the present case six cylinders formed in three castings of two cylinders each. These cylinders are supplied with a combustible mixture through a manifold 12, an intake pipe 13 and a carbureter 14. In the intake pipe 13 is a throttle 15 which is under control of an accelerator pedal 16 connected to the throttle by a rod 17, the accelerator pedal being mounted on the inclined floor board 18 in convenient position for operation by the driver's foot. The throttle is held yieldingly in substantially closed position by a spring 19, the arm 20 of the throttle resting against an adjustable stop 21 which determines its substantially closed position for idling the motor.

The carbureter 14 has a main air inlet 22 and an auxiliary air inlet 23, the former being controlled by a butter-fly valve 24 which is normally held in wide open position, and the latter being controlled by a spring 25, the spring 26 of

which is adjustable by a wedge 27 controlled by a rod 28. The valve 24 is controlled by a rod 29 and spring 29' and both rods 28 and 29 may be operated in any suitable manner as by the control rod 30 which extends upwardly parallel with the steering column 31 and is moved longitudinally as by a hand wheel 32 through rack and pinion mechanism 33. It will be seen that if the rod 30 is moved downwardly it will carry the bell crank 34 with it to thereby move the wedge 27 forwardly and increase the tension on the spring 26, and a further movement of the rod 30 carries with it the bell crank 35 and thereby moves the butter-fly valve 24 to closed position. The position of this rod 30

therefore determines the adjustment of the carbureter for increasing and decreasing the richness of the mixture, it being obvious that when the valve 24 is closed and the tension on the spring 26 increased, very little air will be drawn into the carbureter and the consequent suction will draw in considerable gasoline through the spray nozzle. This position of the carbureter is shown in Fig. 2 and it may be termed the starting position of the motor. In Fig. 1 the carbureter is shown in normal or running position, that is, with the valve 24 wide open and the wedge 27 adjusted so that the spring 26 has a very light tension on the auxiliary air valve 25.

The lower part of the crank case 10 forms an oil sump or well 36 to which the oil drains from the various bearings within the crank case. Operating in the bottom of the sump 36 is an oil pump 37 which takes the oil from the sump and forces it under pressure through a pipe 38 to a strainer 39 and from thence to a manifold 40 which extends longitudinally of the motor and is provided with feed pipes 41 which lead to the various main crank shaft bearings 42 of the motor. From these bearings the oil may be led to the crank pin bearings 43 as shown in section in Fig. 1, and all excess oil thrown off from the bearings returns to the sump 36, thus giving a constant circulation of the oil. Another pipe 44 leads from the manifold 40 to a valve 45 which may be of any suitable form and is operated by a stem 46 which is shown in bifurcated form so that it may be operated by two independent devices. It will be understood that the valve 45 is closed by a spring 45' as shown in Fig. 3 and is opened by pressing the stem 46 inwardly against the action of the spring.

A pipe 47 leads from the outlet of the valve 45 and forms an auxiliary manifold 48 which also extends longitudinally of the motor and has branch feed pipes 49 which may lead to any desired points of the motor to which an extra supply of oil may be fed and these pipes are shown in the drawings as leading directly to the cylinder walls. Under these circumstances, therefore, it will be seen that when the valve 45 is opened, oil will be fed under pressure to the auxiliary oil manifold 48 and from thence conveyed directly to the pistons of the motor which operate in the cylinders. This oil will also drain back into the sump as in the main system.

As above suggested, the auxiliary oiling system is intended to be used only when the motor is developing considerable power or is running at high speed, or when the motor is cold as when starting. Therefore the present invention provides that the valve 45 may be operated either by a connection from the

throttle so that the valve 45 will be opened 65 as the throttle reaches a predetermined position, say one-third open, or by a connection from the carbureter control means so that the valve 45 is opened when the carbureter is adjusted for starting the motor or keeping 70 it running until it is warmed up. The first mentioned connection is in the form of an arm 50 which has an adjustable button 51 thereon and is arranged in the path of one of the branches of the stem 46 so that the 75 latter is operated when the accelerator pedal 16 is depressed to open the throttle. The other connection, which is independent of the first mentioned connection, is in the form of a pivoted arm 52 having an adjust- 80 able button 53 thereon for operating the stem 46, and this arm 52 is moved in unison with the carbureter control devices through a connecting rod 54 which connects the arm 52 with either of the bell crank levers 34 or 85 35, being shown connected to the lever 34 in the form of the invention shown herein.

From the above it will be seen that the valve 45 will be opened as the throttle 15 is opened, or it will be opened as the carbureter 90 14 is set for the starting position of the motor or for running the motor when cold. Thus the position of the valve 45 is determined either by the throttle position or by the richness of the mixture passing through 95 the carbureter. Also it will be seen that the means for operating the carbureter control devices also simultaneously operates the valve 45 which controls the auxiliary oiling system. 100

Having thus described my invention, what I claim and desire to secure by Letters Patent is:

1. In a hydrocarbon motor, the combination with means for feeding oil to the motor 105 cylinders, and the carbureter air valve control mechanism, of connections between said means and said mechanism whereby the supply of oil to the motor cylinders is cut off when the carbureter air valve is opened. 110

2. In a hydrocarbon motor, the combination with the oiling system including main and auxiliary oil supplies, and the carbureter air valve control mechanism, of connections between said oiling system and said 115 mechanism whereby the auxiliary oil supply is cut off as the carbureter air valve is opened.

3. In a hydrocarbon motor, the combination with the oiling system thereof and the 120 means for controlling the richness of the mixture passing to the motor, of means connecting said system and said first mentioned means whereby the supply of oil to the motor is increased as the richness of the mixture 125 is increased and vice versa.

4. In a hydrocarbon motor, the combination with the oiling system thereof and the

- means for controlling the richness of the mixture passing to the motor, of means connecting said system and said first mentioned means whereby the supply of oil to the motor 5 is varied as the mixture is varied.
5. In a hydrocarbon motor, the combination with the oiling system thereof and the means for controlling the richness of the mixture passing to the motor, of a second 10 means for controlling both said system and said first means simultaneously.
6. In a hydrocarbon motor, the combination with the oiling system thereof and the means for controlling the richness of the mixture passing to the motor, of a device 15 under the control of the operator of the motor for controlling both said system and said means simultaneously.
7. In a hydrocarbon motor, the combination with the oiling system including a valve, and the carbureter having an inlet valve, of a single device for controlling both of said valves simultaneously.
8. In a hydrocarbon motor, the combination with the oiling system including a valve 25 for determining the distribution of the oil fed to the motor, and the carbureter having a valve for varying the richness of the mixture fed to the motor, of a single device for controlling both of said valves.
9. In a hydrocarbon motor, the combination with the oiling system thereof and the means for controlling the richness of the mixture passing to the motor, of a single 30 hand operated device for controlling both said system and said means simultaneously.
10. In a hydrocarbon motor, the combination with the oiling system including a valve for determining the amount of oil fed to the 35 motor, and the carbureter having an air
- valve, of a single device for controlling both of said valves simultaneously.
11. In a hydrocarbon motor, the combination with the oiling system including a main oil feed and an auxiliary oil feed, and a valve 45 controlling said auxiliary oil feed, of means for automatically opening said valve as the motor is set for starting.
12. In a hydrocarbon motor, the combination with the oiling system including a main 50 oiling means and an auxiliary oiling means, and a valve controlling said auxiliary means, of a carbureter control device and a throttle control device, both of said devices being connected to operate said valve.
13. In a hydrocarbon motor, the combination with the oiling system including a main oiling means and an auxiliary oiling means, and a valve controlling said auxiliary means, of a carbureter control device and a throttle 55 control device, both of said devices having connections to insure said valve being open when either the carbureter is adjusted for a rich mixture or the throttle is open.
14. In a hydrocarbon motor, the combination with the oiling system including a main oiling means and an auxiliary oiling means, and a valve controlling said auxiliary means, of a device on the motor adapted to have starting and running positions, and means 60 connecting said device with said valve whereby the latter is open when said device is in said starting position.
- In testimony whereof I affix my signature in the presence of two witnesses.
